CLAIM

The ornamental design for a training computer, as shown and described.

DESCRIPTION

FIG. 1 is a right isometric view of a training computer showing the new design;

FIG. 2 is a right-side view of the training computer;

FIG. 3 is a left-side view of the training computer;

FIG. 4 is a front view of the training computer;

FIG. 5 is a rear view of the training computer;

FIG. 6 is a bottom-end view of the training computer; and,

FIG. 7 is a top-end view of the training computer.

The broken lines shown in the drawings depict portions of the training computer that form no part of the claimed design.
